Primary Examiner — L. A. Grabenstetter*(74) Attorney, Agent, or Firm* — Walter A. Rodgers(57) **CLAIM**

The ornamental design for a cartilage planer as shown and described.

DESCRIPTION

FIG. 1 is a perspective view of a cartilage planer showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left-side elevation view thereof; and

FIG. 7 is a right-side elevation view thereof; and,

FIG. 8 is a second perspective view thereof, shown in a reduced scale with additional unclaimed environmental content.

The broken lines are included for the purpose of illustrating environment and form no part of the claimed design.
